Primary Examiner — Kendra Leslie Hamilton(74) *Attorney, Agent, or Firm* — Morgan, Lewis & Bockius LLP(57) **CLAIM**

The ornamental design for a pet harness, as shown and described.

DESCRIPTION

FIG. 1 is a top, front, left perspective view of a pet harness showing my new design in a condition of use;
FIG. 2 is a top, front, left perspective view of the pet harness of FIG. 1;

FIG. 3 is a top, rear, right perspective view thereof;

FIG. 4 is a front elevational view thereof;

FIG. 5 is a rear elevational view thereof;

FIG. 6 is a right-side elevational view thereof;

FIG. 7 is a left-side elevational view thereof;

FIG. 8 is a top plan view thereof; and,

FIG. 9 is a bottom plan view thereof.

The longer equally spaced broken lines that show strap positioners and label depict portions of the pet harness that form no part of the claimed design. The shorter equally spaced broken lines on the pet harness depict stitching and form no part of the claimed design. The broken lines showing a dog in FIG. 1 depict environmental matter and form no part of the claimed design. All of the broken lines form no part of the claimed design.
